UNITED STATES PATENT OFFICE.

ADAM BLUEGE, OF CHICAGO, ILLINOIS.

CUTTER.

1,144,750.

Specification of Letters Patent. Patented June 29, 1915.

Application filed December 5, 1914. Serial No. 875,650.

To all whom it may concern:

Be it known that I, ADAM BLUEGE, a citizen of the United States, residing at Chicago, in the county of Cook and State of Illinois, have invented certain new and useful Improvements in Cutters, of which the following is a specification.

This invention relates to cutting machines of the type designed for simultaneously severing several strands of wire, used particularly for binding the sides of what are known as wire bound boxes.

Wired or wire bound boxes are, at the present time, manufactured by machinery whereby the four sides of each box are secured together by a plurality of continuous strands of wire, said strands being discharged from the machine uncut irrespective of the number of boxes secured thereto, there being only a space between each pair of boxes. Manifestly, therefore, it is necessary to sever or cut the continuous strands of wire at the spaces between the adjoining boxes and this is now done manually.

It is the object of the present invention to provide an attachment for the machines used in manufacturing wire bound boxes which will automatically sever or cut simultaneously all of the continuous strands of wire at the spaces between the boxes and which will receive the strands of wire with the boxes secured thereto directly from the box machine.

While the present invention is disclosed and described as being particularly adaptable as an adjunct to a machine for manufacturing wire bound boxes, it has numerous uses and is not to be construed as being so limited.

With the above and other objects in view, as will be hereinafter apparent, this invention consists in the construction combination and arrangement of parts, all as herein-after more fully described, claimed, and illustrated in the accompanying drawings wherein:

Figure 1 is a side elevation of a machine constructed in accordance with the present invention, illustrating in dotted lines box elements passing therethrough; Fig. 2 is a plan view thereof likewise illustrating the box elements and binding wires in dotted lines; Fig. 3 is a vertical section taken along line 3-3, Fig. 1; Fig. 4 is an end elevation

of the machine; and Fig. 5 is a section taken along line 5-5, Fig. 4, to illustrate the power clutch mechanism.

In dotted lines in all of the figures is illustrated the box elements 10 which are the sides of a box, secured together in units of four by means of the continuous binding wires, a space 12 being located between each unit of four box elements. The continuous binding wires 11 and the attached box elements 10 are fed through the machine in the direction of the arrow A in Fig. 3.

A frame comprising the legs 13, the cross bars 14, and the braces 15, constitutes the main support of the present machine, said braces 15 being cylindrical in cross section. Mounted upon the braces 15, adjacent to the cross bars 14 are the runners or tracks 16 which, at the inlet or feed end of the machine, extend beyond the adjoining brace 15 and are curved downwardly as at 17 to constitute guides for directing the box elements 10 and binding wires 11 to the cutting mechanism hereinafter described.

An upright 18 having a central vertical slot 19, open at one end, in its upper terminal is secured to each cross bar 14 by means of the bolts 20 which pierce not only the cooperating cross bar but also a transverse base 21 formed on the non-slotted end of the upright. These uprights in combination form a superstructure which carries the cutting mechanism for operation upon the binding wires 11 passing thereunder.

The cutting or shearing mechanisms are mounted between the uprights 18 and operate in the slots 19 and comprise a carrier bar 22 arranged transversely between the uprights 18 and having its ends located in the slots 19 for a vertical movement. An operating bar 23 is similarly located above the carrier bar 22 and is mounted for reciprocatory vertical movement in the slots 19 of the uprights 18.

Each of the cutters or shears 24 has one arm 24' pivoted to the carrier base 22 and opposite arm 24'' extended and slotted as at 24' for engagement with the pin 25 of the operating bar 23. In this manner when the operating bar 23 rests approximately flush against the carrier bar 22 the cutters or shears 24 are open; but when the operating bar 23 is raised and reciprocated all of the cutters or shears 24 are closed and opened

simultaneously shearing or cutting all of the binding wires 11 located between the cutting portions thereof. As illustrated in Fig. 3 the arms 24' and 24'' of the shears or cutters 24 are offset and rest flush against the bars 22 and 23, so that the cutting or shearing portions thereof rest in substantially the same vertical plane as the said bars.

Normally the shears or cutters 24 are elevated above the wires 11, but when a space 12, between two units of box elements 10, passes under the shears 24, said shears or cutters are lowered to engage and sever the wires 11 upon the reciprocation of the operating bar 23 in the slots 19 to bring the arms 24' and 24'' of the shears or cutters together. In order to accomplish this movement an oscillatory rod 26 is secured between the rear ends of the cross bars 14 above the adjoining brace 15 and in the same vertical plane therewith, said rod 26 piercing and extending beyond the cross bars 14. An operating finger 27 is adjustably secured to the rod 26 by means of a block 28 and a set screw 29, said finger 27 having its free end rebent to form a contact or bearing member 30 which rests in substantially the same vertical plane as the shears or cutters 24. This contact or bearing 30 is so located with respect to the body 27 of the finger that said finger rests normally at an acute angle to the horizontal plane, but when the bearing or contact 30 drops into a space 12 between two units of box element 10, the free end of the finger 27 is lowered oscillating the rod 26 in one direction; whereas when the contact or bearing 30 rides upon the next unit of box elements 10, the finger 27 is moved upwardly and the rod 26 is oscillated in the reverse direction. The oscillation of the rod 26 is designed to set into operation mechanism for raising and lowering the cutters or shears 24 and to reciprocate the operating bar 23.

Secured to the projecting terminals of the rod 26 are the arms 31 which are adapted to be moved as the rod 26 is oscillated. A pitman 32 connects the free end of each arm 31 with the corresponding and projecting end of the carrier bar 22 so that when the rod 26 is oscillated downwardly, the said carrier bar 22 will likewise move downwardly bringing the binding wires 11 between the cutting or shearing portions of the shears or cutters 24, and vice versa. The operating bar 23 at one end is connected by the links 33 to the adjacent end of the carrier bar 22 while at its opposite end is connected to said carrier bar by means of the bell cranks 34.

In order to reciprocate the operating bar 23 the free ends 34' of the bell cranks 34 are connected to a one cycle or revolution driving mechanism, which constitutes a drive shaft 35 mounted on the pedestals 36 and

having the loose pulley 37 mounted thereon between said pedestals. A clutch element 38 is slidably mounted on the hub 37' by means of a bell crank 39 pivoted to one of the pedestals 36. Keyed to the shaft 35 against longitudinal movement on said shaft is a second clutch member 40 arranged to engage with the clutch member 38 at predetermined intervals to impart one revolution to the shaft 35. This is accomplished by a pin or projection 41 on one end of the pedestals 36 which when the shaft 35 and clutch element 38 have completed one revolution engages a cam 42 on the adjacent face of the said clutch member 38 and disengages it from the clutch member 40.

For connecting the shaft 35 to the free ends 34' of the bell cranks 34 for oscillating the latter and reciprocating the operating bar 23 a crank 43 is formed on the inner end of said shaft, which crank has an eccentric arm 44. A pitman 45 forms a connection between the crank 43 and the bell cranks 34. In this manner when the clutch members 38 and 40 are in interengagement a single rotation of the shaft 35 causes the operating bar 23 to reciprocate bringing the arms 24' and 24'' of the shears or cutters 24 together to sever or cut the binding wires 11. Previous to this movement, however, the finger 27 and arms 31 have moved downwardly to bring the shears or cutters 24 into operative relation with the binding wires 11 and it is this movement that oscillates the bell crank 39 to bring the clutch members 38 and 40 into locking engagement. For this purpose the free arm of the bell crank 39 has a slotted connection with the lower end of the link 46 which is pivotally connected at its upper end to the adjacent end of the carrier bar 22 so that when this bar moves downwardly the bell crank 39 will oscillate to bring the clutch members into interengagement.

After the wires 11 have been severed and prior to the completion of the single revolution of the shaft 35, it is necessary to move the bars 22 and 23 in a similar direction to their initial position so that the passage of the next unit of box elements 10 may have an unobstructed passage under the cutters or shears 24. To accomplish this, the eccentric arm 44 of the shaft 35 has a pitman 47 pivoted to its free end, said pitman having a slotted extension 48 for engagement with a pin 49 carried by the adjacent arm 31. During the cutting or shearing operation the slot of the extension 48 is such that the crank 43 may rotate without affecting the arms 31; but upon the completion of the cutting or shearing operation the wall at the end of the slot in the extension contacts with the pin 49 and elevates the arms 31 and finger 27 so that all of the parts are returned to their original positions.

The operation of this machine has been fully described and set forth in connection with the description of the elements thereof and it is thought unnecessary to repeat it. However, it is to be understood that while the present invention receives the units of box elements from the machine which forms and arranges them and separates them and this is the main function of the invention, it may be used for many other purposes.

While the preferred form of this invention is shown and described it is to be understood that many changes may be made in the details and construction without departing from the spirit and scope hereof as stated in the claims.

I claim as my invention:—

1. In a machine of the class described, a machine frame, a plurality of actuating bars movably mounted in said frame, a cutter hung pendant from said bars and having one cutting arm pivoted to one of said actuating bars and the other cutting arm pivoted to another actuating bar, and means for moving said bars to operate the cutter.

2. In a machine of the class described, a machine frame, a plurality of actuating bars movably mounted in said frame, a cutter hung pendant from said bars and having one cutting arm pivoted to one of said actuating bars and the other cutting arm pivoted to another actuating bar, and means for moving said bars at angles to the perpendicular, to operate the cutter.

3. In a machine of the class described, a machine frame, a plurality of actuating bars movably mounted in said frame in different but horizontal parallel planes, a cutter hung pendant from said bars and having one cutting arm pivoted to one of said actuating bars and the other cutting arm pivoted to another actuating bar and means for moving said bars to operate the cutter.

4. In a machine of the class described, a machine frame, a plurality of actuating bars movably mounted in said frame in different but horizontal parallel planes, a cutter hung pendant from said bars and having one cutting arm pivoted to one of said actuating bars and the other cutting arm pivoted to another actuating bar and means for moving said bars relatively to each other and also at angles to the perpendicular to operate the cutter.

5. In a machine of the class described, a machine frame, a plurality of actuating bars movably mounted in said frame, and a cutter operatively depending from said bars and having its cutter arms pivoted to each other at an intermediate point, and one of said arms having fixed pivotal attachment to one of said actuating bars, and the other of said arms having slidable pivotal attachment to the other of said actuating bars.

6. In a machine of the class described, a

machine frame, a plurality of actuating bars movably mounted in said frame, and a cutter having its arms pivoted to each other at an intermediate point, and one of said arms having a slot in its upper portion, a pivot pin attached to one of the actuating bars slidably engaging in the slot and a pivot pin attached to the other bar and engaging the other cutter arm.

7. In a machine of the class described, a machine frame, a plurality of actuating bars movably mounted in said frame, and a cutter hung pendant from said bars and having its cutting arms pivoted to each other at an intermediate point and at their upper extremities to the actuating bars and means for moving said bars to operate the cutter.

8. In a machine of the class described, a machine frame, a plurality of actuating bars movably mounted in said frame, in parallel horizontal planes one over the other, and a cutter hung pendant from said bars and having its cutting arms pivoted to each other at an intermediate point and at their upper extremities to the actuating bars and means for moving said bars to operate the cutter.

9. In a machine of the class described, a machine frame, a plurality of actuating bars movably mounted in said frame, in parallel horizontal planes one over the other, and a cutter hung pendant from said bars and having its cutting arms pivoted to each other at an intermediate point and at their upper extremities to the actuating bars and means for moving said bars relatively to each other to operate the cutter.

10. The combination with a cutter having a pair of pivoted arms, of a vertically movable support coöperating with one of said arms, an operating bar adjacent said support for coöperation with the other of said arms, means for operating said bar and support for performing a cutting action; and means for controlling the operating means from the material operated upon.

11. In a machine of the class described, a machine frame, actuating bars movably mounted in said frame in different but parallel horizontal planes, and a plurality of cutters depending at intervals from said actuating bars and having their arms independently connected to said actuating bars.

12. In a machine of the class described, a machine frame, actuating bars movably mounted in said frame in different but parallel horizontal planes, and a plurality of cutters depending at intervals from said actuating bars and having their arms independently connected at their upper ends to said actuating bars.

13. In a machine of the class described, a machine frame, actuating bars movably mounted in said frame in different but parallel horizontal planes, and a plurality of cutters depending at intervals from said ac-

tuating bars and having their arms independently connected to said actuating bars for simultaneous operation.

14. In a machine of the class described, a machine frame having uprights provided with vertical slots, actuating bars slidably mounted in said vertical slots, and a plurality of cutters depending at intervals from the said actuating bars and having their arms respectively connected to said actuating bars.

15. In a machine of the class described, a machine frame having uprights provided with vertical slots, actuating bars slidably mounted in said vertical slots in different but parallel horizontal planes, and a plurality of cutters depending at intervals from the said actuating bars and having their arms respectively connected to said actuating bars.

16. In a machine of the class described, a machine frame having uprights provided with vertical slots, actuating bars slidably mounted in said vertical slots in different

but parallel horizontal planes, a pivotal link 25 connecting said bars at one end thereof, a bell crank pivoted to the opposite end of said bars, means for rocking said bell crank, and a plurality of cutters depending at intervals from the said actuating bars and 30 having their arms respectively connected to said actuating bars.

17. In a machine of the class described, a machine frame having uprights provided with vertical slots, actuating bars slidably 35 mounted in said slots in different but parallel planes, means pivotally linking said bars, and a plurality of cutters depending at intervals from the said actuating bars and having their arms respectively connected to 40 said actuating bars.

In testimony whereof I have hereunto affixed my name in the presence of a witness.

ADAM BLUEGE.
